(57) **CLAIM**

The ornamental design for a set of labels for product container, as shown and described.

DESCRIPTION

The patent or application file contains at least one drawing executed in color. Copies of this patent or patent application publication with color drawing(s) will be provided by the Office upon request and payment of the necessary fee.

FIG. 1 is an enlarged detailed view of the center portion of the label in FIG. 3, isolated for clarity of illustration;

FIG. 2 is the front perspective view of a set of labels for product container;

FIG. 3 is a front elevation view thereof;

FIG. 4 is a rear elevation view thereof a rear label;

FIG. 5 is a left side view thereof;

FIG. 6 is a right side view thereof;

FIG. 7 is a top plan view thereof; and,

FIG. 8 is a bottom plan view thereof.

The product container shown in broken lines is included to show environment that form no part of the claimed design.

1 Claim, 8 Drawing Sheets
(6 of 8 Drawing Sheet(s) Filed in Color)
